(57) **CLAIM**

The ornamental design for a mattress depression test apparatus, as shown and described.

DESCRIPTION

FIG. 1 is a side elevation view of the invention positioned to measure mattress depression.

FIG. 2 is a top view of the invention in the position of FIG. 1; and,

FIG. 3 is a rear elevation view of the invention.

The second side view has not been shown because it is essentially a mirror image of the first side view.

The front view has not been shown as it would not reveal anything that the existing views have not already shown.
